Primary Examiner—Cathron C. Brooks

(57) **CLAIM**

The ornamental design for a display, as shown and described.

DESCRIPTION

A claim for copyright (© 2005 by Joel W. Benson) is made for the display design, as illustrated in all drawings provided

herewith. The copyright owner has no objection to the facsimile reproduction by anyone of this patent document, the drawings, or this patent disclosure, as it appears in the U.S. Patent and Trademark Office patent file or record, but otherwise reserves all copyright rights whatsoever.

FIG. 1 is a perspective view of a first embodiment of a display;

FIG. 2 is a front elevation view of the display of FIG. 1; FIG. 3 is an end elevation view of the display of FIG. 1, which is a mirror image of the opposite end;

FIG. 4 is a bottom elevation view of the display of FIG. 1;

FIG. 5 is a top elevation view of the display of FIG. 1;

FIG. 6 is a rear elevation view of the display of FIG. 1;

FIG. 7 is a perspective view of a second embodiment of the display of FIGS. 1-6, the only difference being in the omission of a front viewing plate at the base of the display, it being understood that all other surfaces are the same as shown for FIGS. 1-6;

FIG. 8 is a front elevation view of the display of FIG. 7; FIG. 9 is an end elevation view of the display of FIG. 7, which is a mirror image of the opposite end;

FIG. 10 is a bottom elevation view of the display of FIG. 7;

FIG. 11 is a top elevation view of the display of FIG. 7;

FIG. 12 is a rear elevation view of the display of FIG. 7;

FIG. 13 is a perspective view of a third embodiment of the display of FIGS. 1-6, the only difference being in the omission of a slot in the front guide rail of the display, it being understood all other surfaces are the same as shown in FIGS. 1-6;

FIG. 14 is a front elevation view of the display of FIG. 13; FIG. 15 is an end elevation view of the display of FIG. 13, which is a mirror image of the opposite end;

FIG. 16 is a bottom elevation view of the display of FIG. 13;

FIG. 17 is a top elevation view of the display of FIG. 13;

FIG. 18 is a rear elevation view of the display of FIG. 13;

FIG. 19 is a perspective view of a fourth embodiment of a display of FIGS. 1-6, the only difference being in the omission of a front viewing plate at the base of the display and the omission of a slot in the front guide rail of the display, it being understood all other surfaces are the same as shown in FIGS. 1-6;

FIG. 20 is a front elevation view of the display of FIG. 19;

FIG. 21 is an end elevation view of the display of FIG. 19, which is a mirror image of the opposite end;

FIG. 22 is a bottom elevation view of the display of FIG. 19; FIG. 23 is a top elevation view of the display of FIG. 19; FIG. 24 is a rear elevation view of the display of FIG. 19; FIG. 25 is an additional embodiment of the display of the design of the first and third embodiments, the only difference being the addition of an ornamental message at the front surface of the display; and,

FIG. 26 is an additional embodiment of the display of the design of the first and third embodiment, the only difference being the addition of an ornamental message at the front surface of the display.
